United States Patent Office

Des. 173,558
Patented Nov. 30, 1954

173,558

AUTOMATIC REGISTER

Allen B. Cooke, Danville, Ill.

Application December 1, 1953, Serial No. 27,851

Term of patent 14 years

(Cl. D64—11)

FIG. 1

FIG. 2

FIG. 3

FIG. 4

To all whom it may concern:

Be it known that I, Allen B. Cooke, a citizen of the United States, residing at Danville, in the county of Vermilion and State of Illinois, have invented a new, original, and ornamental Design for an Automatic Register, of which the following is a specification, reference being had to the accompanying drawing, forming a part hereof.

Fig. 1 is a view in perspective of an automatic register taken from the top and left side;

Fig. 2 is a view in perspective taken from the top and right side;

Fig. 3 is a view in perspective taken from the top and rear end; and

Fig. 4 is a view in perspective taken from the top and front end.

I claim:

The ornamental design for an automatic register, as shown.
